[57] CLAIM

The ornamental design for a combined bathtub waste
and overflow face plate, as shown.

DESCRIPTION

FIG. 1 is a front elevational view of my new design for
a combined bathtub waste and overflow face plate.

FIG. 2 is a side elevational view thereof.

FIG. 3 is a top plan view thereof.

FIG. 4 is a bottom plan view thereof.

FIG. 5 is a cross sectional view thereof taken on line
5—5 of FIG. 1.

FIG. 6 is a rear elevational view thereof.
